Howard E. Barlow
Attorney.

UNITED STATES PATENT OFFICE.

GEORGE E. GOODRICH, OF PROVIDENCE, RHODE ISLAND.

FASTENER.

Application filed April 9, 1921. Serial No. 460,021.

To all whom it may concern:

Be it known that I, GEORGE E. GOODRICH, a citizen of the United States, residing at Providence, in the county of Providence and State of Rhode Island, have invented 5 certain new and useful Improvements in Fasteners, of which the following is a specification.

This invention relates to garment fasteners of the type particularly adapted for use in fastening the parts of arctics or overshoes together, but may be employed for fastening the parts of gloves, rubber coats, or other garments, and this invention is an 10 improvement over my copending patent application filed November 13, 1920, Serial Number 423,956.

The object of my present invention is to provide an improved construction of fastener 15 in which the two fastening members are adapted to be separated from each other, each being adapted to be connected to separate portions of a garment which are to be releasably secured together.

A further object of the invention is the provision of a latch tongue housed in the tubular keeper member, having one end extending outwardly through the top wall thereof and adapted to receive a lateral dis- 20 engaging motion, said end being provided with an operating button, by which construction the releasing latch may be readily engaged and operated and at the same time the parts are nicely rounded or so shaped 25 that they will not become caught or entangled in any adjacent portion of the garment.

With these and other objects in view, the invention consists of certain novel features 30 of construction, as will be more fully described, and particularly pointed out in appended claims.

In the accompanying drawing:

Figure 1 is a perspective view illustrating the keeper member with the lock plate withdrawn therefrom.

Figure 2 is a perspective view of the lower plate of the keeper member, showing the resilient latch tongue formed integrally 45 therewith.

Figure 3 is a perspective view of the channel portion of the keeper member, showing its bendable fingers adapted to be folded over the edge of the lower plate to secure 50 the two together.

Figure 4 is a central longitudinal section through the keeper member.

Figure 5 is a transverse section on line 5-5 of Figure 6 through the keeper member with the lock plate mounted therein. 60

Figure 6 is a top view of my improved fastener, showing the top wall of the tubular keeper member, removed; and showing the lock plate in position in the keeper and its teeth engaged by the latch tongue. 65

With reference to the drawing, 10 designates the keeper member which comprises essentially a bottom plate 11 which may be formed of steel or other suitable resilient material from which a spring latch tongue 70 may be formed. A portion about the center of this bottom plate is punched or cut out as at 12 leaving a central resilient longitudinally disposed tongue member 13 therein which is integrally connected at one end 14 75 to a portion of the plate. The outer or free end of this tongue is turned upwardly as at 15 and this upturned portion is provided with a beveled edge to serve as a pawl or latch for engaging the teeth of the lock plate, 80 presently described.

The rear end of this plate is provided with an opening 16 through which thread or other fastening means may be passed for securing the plate to a garment. 85

In Figure 6 of the drawing the latch 13 has but a single tooth 15 which is shown in cross section in this figure, the balance of the latch 13 is below the plane of part 22 the teeth 25 shown in this figure, are formed 90 on one of the branches of this part 22 and are in a plane above that of the body of the latch, as best illustrated in Figure 4.

The other portion of this keeper member comprises essentially an inverted channel-shaped member 17, the bottom side edges of which are provided with bendable fingers 18 which are adapted to pass into notches 19 formed in the edges of the plate 11 and to be folded over beneath the bottom of this 100 plate for the purpose of firmly securing the two together. The upper wall of this housing member 17 is slotted as at 20 to permit the free end of the latch tongue 13 to extend upwardly therethrough, the extremity of 105 which free end is provided with a rounded operating button or cap 21 so shaped as not to engage or catch into any portion of the garment with which it may come in contact.

By this construction it will be seen that 110

this housing member or cap may be made of very thin material as compared with the bottom plate 11, which plate must of necessity be of sufficient thickness to provide a proper resilient latch tongue.

Also by this construction this housing member may be made of a different quality of material such as brass or even silver which will take on a high polish while the bottom plate may be of steel and of sufficient thickness to provide the necessary supporting or holding strength.

The other member of this fastener is preferably made in the form of an elongated plate 22 having one end 23 adapted to be permanently secured to another portion of the garment, the end of this plate, opposite to the fastening end, being bifurcated as at 24 so that it will straddle the latch tongue 13 in the keeper, and the inner edge 25 of one of the arms of the fork is provided with ratchet teeth for engaging the beveled edge of the latch tongue for the purpose of releasably securing the two members together when the lock plate is inserted into the keeper.

The forward end of this lock plate is preferably tapered as at 26, to facilitate its ready entrance into the housing member; also the side edges of this lock plate are left plain so as to engage and be supported by the inner side walls of this housing member.

In operating my improved garment fastener where the two opposite members are secured to adjacent portions of a garment it is only necessary to pass the tapered end of the lock plate into the housing member and the latch in the latter will engage the teeth in the former releasably connecting them together and by providing an elongated lock plate, when the parts of the garment are too tightly connected together, it is only necessary to apply the thumb or finger to the button 21 and by pressing it lightly to one side the latch is withdrawn from the teeth permitting the parts to separate slightly or the parts may be withdrawn entirely one from the other, if desired.

The device is very simple and practical in construction, and effective in its operation.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A garment fastener comprising a tubu-

lar keeper inclosing a resilient latch tongue and adapted to be permanently secured to one portion of the garment, a bifurcated lock plate adapted to be permanently attached to another portion of the garment, the same being adapted to straddle said lock tongue and having ratchet teeth on the inner edge of one of its arms for engaging said tongue, the plain side edges of said plate being guided by the side walls of said keeper tube, and an operating button for releasing said locking tongue.

2. A garment fastener comprising a tubular keeper formed of a bottom plate having a channel-shaped housing part secured thereto by turning the edges of one of said members over those of the other, a laterally yieldable latch tongue carried by said plate and having its operating end extending through the front wall of said housing part and adapted to receive a transversely slideable disengaging motion, and a ratchet toothed lock-plate adapted to be secured to another portion of the garment and adapted to enter and be guided into said tubular keeper by engaging the inner side walls thereof to be releasably retained by said latch.

3. A garment fastener comprising a tubular keeper adapted to be secured to one portion of the garment, the same being formed of a bottom plate having a channel-shaped housing part secured thereto, a resilient latch tongue formed integral with said bottom plate and extending longitudinally of said housing, a lock plate adapted to have one end secured to another portion of the garment, and its opposite end being bifurcated and toothed to straddle and be engaged by said latch whereby the two parts are releasably connected together upon the entrance of said plate into said keeper.

4. A garment fastener comprising a tubular keeper member inclosing an integral resilient latch tongue and adapted to be permanently secured to one portion of a garment, said latch tongue having its latch end extending outwardly through the front wall of said keeper and adapted to receive a transversely slideable disengaging motion, an operating button fixed to the projecting end of said latch, and a lock plate adapted to be permanently attached to another portion of the garment and provided with ratchet teeth to engage said latch tongue to releasably hold the parts together.

In testimony whereof I affix my signature.

GEORGE E. GOODRICH.
